UNITED STATES PATENT OFFICE.

JOHN GYULAY, OF BRIDGEPORT, CONNECTICUT.

REVERSING STEAM-TURBINE.

1,091,129.

Specification of Letters Patent. Patented Mar. 24, 1914.

Application filed January 2, 1914. Serial No. 809,952.

To all whom it may concern:

Be it known that I, JOHN GYULAY, a subject of the King of Hungary, residing at Bridgeport, in the county of Fairfield and

5 State of Connecticut, have invented certain new and useful Improvements in Reversing-
Steam-Turbine Engines, of which the following is a specification.

This invention relates to certain new and 10 useful improvements in reversing steam turbine engines.

An object of the invention is to provide a steam turbine engine with a substantially spherical steam dome and arranging at the 15 lower end of the steam dome, a double acting valve to alternately feed steam to either a forward or reversing turbine wheel.

A further object of the invention is to provide a steam turbine engine with a pair of 20 integral turbine wheels arranged side by side and each wheel having pockets opening in opposite directions, the turbine wheels being supported independently of said engine and arranged to partially extend into an enlargement carried by the steam dome.

With the above and other objects in view which will appear as the nature of the invention is better understood, the same consists in the novel construction, combination 30 and arrangement of parts to be hereinafter more fully described and then claimed, reference being had to the accompanying drawings by like characters throughout the several views, and wherein:—

35 Figure 1 is a side elevational view of a steam turbine engine embodying my invention. Fig. 2 is a top plan view of the same. Fig. 3 is an enlarged detail sectional view of the double acting valve for controlling the 40 steam supply to the turbine wheel, and Figs. 4 and 5 are side elevational views partly in section, of a portion of the steam dome, the valve and turbine wheels illustrating the forward and reverse turbine wheels.

45 Referring more specifically to the drawings, the reference numeral 10 designates a steam boiler of the usual construction. In the present instance, the steam dome in connection with the steam boiler is formed independently of said boiler and is of substantially spherical shape. This steam dome is 50 designated 11 and has a pipe connection 12 with the boiler 10 which is controlled by the valve cock 13. The steam dome 11 is supported upon the standard 14 arranged

adjacent one end of the boiler. A pipe 15 connected with the steam dome 11 constitutes an auxiliary outlet for the same, this pipe being provided with a valve cock 16 and arranged intermediate the ends of said 60 pipe is a steam pressure indicator 17.

One side of the steam dome 11 adjacent its lower end is provided with a hollow substantially semi-circular enlargement 18 and arranged between the steam dome 11 and enlargement 18 is a tubular member 19 constituting a casing for a double acting valve 20. The valve casing 19 is provided with a pair of ports 21 and 22, the ports 21 being inclined upwardly while the ports 22 are inclined downwardly and arranged in spaced relation. The valve 20 is provided with a pair of ports 23 and 24 opening in different directions and adapted to alternately register with the ports 21 and 22. The valve 20 70 is inserted in the casing 19 and has its inner end screw-threaded as at 25 to receive a packing gland 26, the inner end of which is received in the internally-threaded boss 27 formed on one side of the steam dome. A 80 packing gland 28 is received in the enlargement 29 carried by the opposite side of the steam dome and effectively prevents all escape of steam.

The outer end 30 of the valve 20 is provided with a crank arm 31 and connected to the end of said crank arm is one end of a link 32. The other end of said link is connected to the lever 33, which lever is connected at its end as at 34 to an arm 35 projecting from the forward end of the boiler. The turbine wheel in the present instance, is of the double acting type and is designated in general, 36. The turbine wheel 36 is mounted upon a standard 37 arranged adjacent the standard 14 and so positioned with respect thereto that the turbine 36 will extend into the semi-spherical enlargement 18 carried by the steam dome 11. The upper ends of the standards 37 constitute trunnions for the turbine wheel 36 and preferably as shown, a circular saw 39 is mounted upon one end of the shaft 38, although any other power driven implement can be utilized.

100 The turbine wheel is of the double acting type and comprises more specifically three circular plates 40 equi-distantly spaced and providing a pair of compartments. In each 105 of the compartments are arranged the blades 110

as shown in Figs. 4 and 5. Referring to Fig. 4, the turbine wheel shown is adapted to drive the shaft 38 in a forward direction. This wheel comprises the radial blades 41 provided with the pockets 42 against which is directed a jet of steam from the steam dome 11 through the registering ports 21 and 23. The form of turbine wheel shown in Fig. 5 is for driving the shaft 38 in an opposite direction and comprises the blades 43 provided with the pockets 44 against which is directed a jet of steam passing through the registering ports 22 and 24.

The operation of the device is as follows: When it is desired to drive the shaft 28 in a forward direction, the valve 20 is rotated to bring the ports 21 and 23 into registry, which permits the steam contained in the dome 11 to pass therethrough and be received within the pockets 42 of the blades 41. When it is desired to reverse the direction of travel of the shaft 38, the lever 33 is moved and shifts the link 32, which link being connected to the crank arm 31 carried by the end 30 of the valve 20, moves said valve to break the passages 21 and 23 and bring into communication the ports 22 and 24, and direct the jet of steam from the dome 11 into the pockets 44 of the blades 43. It is to be noted that the steam passing from the dome 11 into the enlargement 18 to drive the turbine wheel escapes at this point. The valve cock 13 is provided to shut off the supply of steam from the boiler 10 while the pipe 15 is used to drain the dome 11 as well as constituting a secondary means for the steam indicator 17.

While I have shown and described the preferred embodiment of my invention, I do not wish to confine myself thereto, as various forms and modifications of the parts

may be had without departing from the spirit and scope of the invention as claimed.

What I claim as new and desire to secure by Letters Patent is:—

45

1. In a reversing steam turbine engine, a substantially spherical steam dome, an enlargement carried by said dome, a double-acting valve arranged between the steam dome and the enlargement, and a double turbine wheel provided with pockets opening in opposite directions supported independently of said engine and partially extending into said enlargement.

55

2. In a reversing steam turbine engine, a steam dome arranged independently of said engine and having a conduit connection therewith, an enlargement carried by said dome, a double-acting valve positioned between the dome and the enlargement, a driven shaft independent of said engine, a double turbine wheel provided with pockets opening in opposite directions carried by said driven shaft and adapted to partially extend into said enlargement.

65

3. A steam turbine engine comprising a steam dome, a semi-spherical enlargement carried by said dome opening to the atmosphere, a turbine wheel provided with two sets of pockets, each of said pockets opening in opposite directions, said turbine wheel being positioned to extend into the enlargement, and a double-acting valve for directing the jet of steam onto either set of pockets for driving said wheel in either direction.

75

In testimony whereof I affix my signature in presence of two witnesses.

JOHN GYULAY.
